UNITED STATES PATENT OFFICE

119,086

DESIGN FOR AN ASHTRAY

Samuel L. Fisher, Butler, Pa.

Application May 16, 1939, Serial No. 35,014

Term of patent 3½ years

To all whom it may concern:

Be it known that Samuel L. Fisher, a citizen of the United States of America, residing at Butler, in the county of Butler and State of Pennsylvania, has invented a new, original, and ornamental Design for Ashtrays, of which the following is a specification, reference being had to the accompanying drawing, forming part thereof.

Fig. 1 is a top plan view of the ashtray, showing my new design,

Fig. 2 is a side elevational view thereof, and

Fig. 3 is a bottom plan view.

I claim:

The ornamental design for an ashtray, as shown.

SAMUEL L. FISHER.
